UNITED STATES PATENT OFFICE.

EMERY W. BAXTER, OF BURR OAK, MICHIGAN.

TWO-WHEELED VEHICLE.

SPECIFICATION forming part of Letters Patent No. 395,114, dated December 25, 1888.

Application filed March 9, 1888. Serial No. 266,690. (No model.)

To all whom it may concern:

Be it known that I, EMERY W. BAXTER, of Burr Oak, in the county of St. Joseph and State of Michigan, have invented a new and Improved Two-Wheeled Vehicle, of which the following is a full, clear, and exact description.

Reference is to be had to the accompanying drawings, forming a part of this specification, in which similar letters of reference indicate corresponding parts in all the figures.

Figure 1 is a sectional elevation of my new and improved two-wheeled vehicle, taken on the line $x-x$ of Fig. 2. Fig. 2 is a plan view of the same. Fig. 3 is a plan view of a tongue to be substituted for the thills. Fig. 4 is a sectional side elevation of the same on the line $y-y$ of Fig. 3. Fig. 5 is a transverse sectional elevation on the line $z-z$ of Fig. 3. Fig. 6 is an enlarged broken view showing the preferred means of fastening the thills and the cross-bar of the tongue to the short permanent thill of the vehicle. Fig. 7 is an enlarged view of one of the key-plates of the thills. Fig. 8 is a detailed view of the yoke for attaching the body to the springs. Figs. 9 and 10 show modified methods of attaching the springs. Fig. 11 is a side view of one of the intermediate curved plates. Fig. 12 shows modified method of attaching upper front end of body to bar C; and Figs. 13 and 14 are plan and side views, respectively, of the seat-supporting irons.

The invention will first be described in connection with the drawings, and then pointed out in the claims.

To the axle A are attached the short curved thill-sections B B, like the rear ends of ordinary two-wheeled-vehicle thills. These are connected together by the cross-piece C and curved bar D, and to which are secured by suitable clamps the notched plates g g and the two springs E E, to the rear ends of which is attached a yoke, Y, consisting of a cross-piece, a, (see Fig. 8,) and rods a' a', the lower ends of which are screw-threaded and provided with nuts a², so that by turning said nuts the cross-pieces a may be raised and lowered for elevating or lowering the body of the vehicle.

The body of the vehicle is composed of the curved side bars, F F, seat G, and the series of slats H. The side bars, F, are each formed of two curved plates, f f, preferably of steel.

These are bolted or riveted together, and between them, at the bottom of the body, are placed the curved plates f', (see Figs. 11 and 12,) preferably of cast-iron, which plates are provided with the bolts b b, to which the slats H are secured, and at the lower edge of each of the plates f' are formed notches or projections b', in which the cross-piece a of the yoke Y is held; or it may be formed with a series of notches, b', at upper front end (see Fig. 12) and pivoted to irons B⁴, which are secured to under surface of bar C, so that the body may be shifted backward and forward in the notches B⁴ to vary the leverage of the body on its thills. A guard, b², is attached to each plate f' to hold the yoke in place in the notches b'. The upper front ends of the side bars, F, are pivoted to the plates g g, which are formed with holes and secured to the bar C or curved bar D, or both, and to the rear ends of said side bars are pivoted the irons h beneath the seat G.

The body of the vehicle is suspended from the springs E by the yoke y, and this yoke may be shifted backward and forward in the notches b' to vary the leverage of the body upon the springs to adjust said leverage to the weight of the rider.

To the seat G are attached the irons h, which are slotted at h⁵ h⁵ to permit the seat to be adjusted backward and forward, and are formed with the downwardly-projecting arms h', which pass between the plates f f, forming the side bars, F. Each of these arms is formed with several holes to receive a bolt passed through corresponding holes in the plates f for adjusting the pitch of the seat G.

J J represent the front sections of the thills, which may be detached from the rear sections, B, for the purpose of attaching the tongue K, (shown in Fig. 3,) which is provided with a cross-bar, K', the ends of which are adapted to be fastened to the ends of the thill-sections B. The strap k at the end of the tongue is adapted to be attached to the center of the curved bar D, preferably by a bolt, k', as indicated in Fig. 2.

I prefer to attach the front sections, J, of the thills to the rear section, B, by means of plates j j', (see Fig. 6,) secured to said sections, respectively, at top and bottom, and which are slotted, as shown at m, to receive the

wedge-shaped keys L L'. The wedge L is in the shape of a bolt, which passes through the upper and lower plates and receives the nut m' at its lower end, and the wedge L' is in the 5 nature of a wedge-shaped washer placed upon the bolt portion l and forced into the slots by turning up the nut m' . The keys L L' being thus forced into the corresponding slots made in the overlapping plates j, j' , they draw said 10 plates and the sections B J together, forming a firm and reliable fastening.

The fastening of the tongue K to the rear sections, B, of the thills is effected also by the 15 keys L L', said keys passing through the slots i' of the plates i , secured at the ends of the cross-piece K' of the tongue, said keys also passing through the slots m of the plates j ; but I do not confine myself to this mode of attaching sections J to the rear sections, B, of 20 the thills, also the cross-piece K' of the tongue, as similar attachments can be made and accomplish the same result.

The tongue K is provided upon the under 25 surface with the truss-rod K², secured at one end to an eye, n , of the ferrule p , or it may be secured to the tongue K, and at the other to the cross-bar K' or tongue K and held away from the tongue at the center by the bridge p' . By the use of this truss-rod the tongue 30 may be made very light and yet strong and very stiff. The cross-bar K' is also trussed by the rod K³ and central bridge, p^3 , as shown clearly in Fig. 5, so that the tongue as a whole is made strong, very light, and stiff, so it will 35 not tremble and jar from the motion of the wheels and axle.

Instead of attaching the springs E to the 40 cross-pieces C D, I may attach them to the under surface of the thills, as shown in Fig. 9, or I may attach them to the upper surface of the thills, as shown in Fig. 10, the springs curving upward, as shown in said figure.

The whiffletrees may be attached to the 45 tongue in any suitable manner, or for a single horse may be attached to the centers of the bars D and C in any suitable manner.

Having thus fully described my invention, I claim as new and desire to secure by Letters Patent—

1. In a two-wheeled vehicle, the side bars, 50 F, each curved and formed of two parallel curved plates, f, f' , united together substantially as described.

2. In a two-wheeled vehicle, the side bars, 55 F, each formed of two curved plates united together, in combination with an intermediate plate, f' , substantially as described.

3. The combination, with the curved plates f, f' , of an intermediate plate, f' , formed with the adjusting - notches, substantially as and 60 for the purposes herein set forth.

4. The curved plates f, f' , formed or provided with the bolts b , in combination with the curved plates f, f' and slats H, substantially 65 as described.

5. The springs E and side bars, F F, pivoted to the plates g , in combination with the yoke Y, composed of the rods a, a' and vertically - adjustable cross-bar a , substantially 70 as described.

6. The seat G, adjustably connected to irons h , provided with downwardly-projecting arms h' , adapted to be secured to the side bars, F, for adjusting the pitch of the seat, substantially 75 as described.

7. The combination, with the side bars, F, springs E, and yoke Y, the cross-piece of which is vertically adjustable, of the seat G, adapted to be adjusted upon a pivot for changing its pitch, substantially as described. 80

8. The front thill-sections, J, provided with the slotted fastening-plates j' and the rear thill - sections, B, provided with the slotted fastening-plates j , in combination with the wedge-shaped keys L L', bolt l , and nut m , 85 substantially as described.

EMERY W. BAXTER.
